UNITED STATES PATENT OFFICE.

GEORGE H. FAHRENBRUCH, OF OMAHA, NEBRASKA.

FREIGHT-CAR-DOOR LOCK.

Application filed December 16, 1921. Serial No. 522,774.

To all whom it may concern:

Be it known that GEORGE H. FAHRENBRUCH, a citizen of the United States, residing at Omaha, in the county of Douglas and 5 State of Nebraska, has invented certain new and useful Improvements in Freight-Car-Door Locks, of which the following is a specification.

My invention relates to new and useful 10 improvements in freight car door locks and has for an object to provide a lock that will securely hold and lock the door in its closed position and prevent any lateral or transverse movement as well as shifting, both of 15 which movements are common in freight car doors with the form of locks now generally in use.

Another object of the present invention is 20 to provide a freight car door lock that does away with the hasps on the front of the door or on the frame of the car adjacent the front edge of the door and to provide a lock that is preferably positioned at the lower right hand corner of the door.

25 In the locks now generally employed, the hasp is often torn from a door or the frame adjacent the front edge of the door and the wood work becomes damaged or torn out as the continued jarring and shifting of the 30 door will tear the hasp or latch from its set position.

Another object of my invention therefore 35 is to provide a lock wherein there is no strain whatever on the latch or on the hasp, the strain falling on an arm that is especially provided and of sufficient size and thickness to withstand the strain that will be placed upon it and thus tightly hold the door in 40 its closed and locked position.

45 Still another object of the present invention is to provide a lock that is preferably situated at the lower right hand corner of the door thus doing away with the usual hasp at the front of the door and at the same time due to its position and construction will prevent the door from being surreptitiously forced slightly upwardly and then transversely to the car without breaking the seal of the lock, which is possible 50 with the locks now in general use.

55 Still another object of my invention is to provide a lock consisting of an arm that is adapted to be swung into a cut-out portion or a pocket which is formed in the lower sill of the door, which arm is of great

strength and when within the pocket will prevent any shifting of the door and will also prevent the door from being moved transversely of the car. Also a latch will be secured to this arm which will be placed 60 over a hasp to lock the door, and the strains thus falling on the aforesaid arm and sill with the pocket therein rather than on the hasp or latch.

Still another object of the invention is to 65 provide a lock for freight car doors comprising two plates one of which is preferably secured to the lower right hand corner of the door and on which plate is secured a conventional hasp and latch member formed 70 in the lower portion of the plate in a steel pocket frame which fits within a pocket formed within the lower sill of the door. The second plate is provided with a standard 75 to which is pivotally secured an arm adapted to fit within said pocket and to the lower end of said arm is secured a latch to pass over the hasp above mentioned.

Still another object of the invention is to 80 provide a freight car door lock which may be quickly and rapidly applied to the freight car doors now in use without in any way changing the character of the door and with only a minimum amount of labor, and, also to provide a lock which may be quickly and 85 readily drawn into place to tightly hold the door against any transverse or lateral movement as well as longitudinal movement.

With these and numerous other objects in 90 view my invention relates to certain new and novel arrangements and combination of parts as will be hereinafter more fully described and pointed out in the claims.

Referring now to the drawings:

Fig. 1 is a view in elevation, showing a 95 freight car door in its closed position with my improved lock placed in the lower right hand corner, the lock being shown in its fastened position.

Fig. 2 is a similar enlarged fragmentary 100 detail view showing the door in a slightly opened position, the lock in this instance being in its opened or unfastened position.

Fig. 3 is a similar view, the door, however, being in its closed position, the lock 105 however, being opened or in its unfastened position.

Fig. 4 is a similar view, the lock in this instance, however, being in its fastened or locked position.

Fig. 5 is a bottom plan view of a portion of the doors and the lock, a part of the wood work being shown in section for the sake of clearness, the lock being fastened.

5 Fig. 6 is a sectional view of the same taken on line 6—6 of Fig. 4 and looking in the direction of the arrow.

Fig. 7 is a vertical sectional view taken on line 7—7 of Fig. 4, the dotted lines showing the arm in several positions.

10 Fig. 8 is a perspective of the upper plate of the lock, before the hasp has been applied.

15 In the drawings, a portion 1 of a freight car is shown having the usual roller track 2 on which are shown the hangers 3 which support the door 4, while at the bottom of the door are shown the conventional guide brackets 5. All of the parts above enumerated 20 are of conventional design and it will be understood that my lock, shortly to be described, may be attached to any freight car door or in fact to any sliding door.

25 In Fig. 1 the ordinary locking means and hasp have been removed from the door and a small strip 6 is shown fastened over the place where the former latch was situated.

30 It is to be understood that my lock may be quickly and readily fastened to the doors now in use with but little effort, necessitating the cutting of only one pocket in the lower corner of the door, or the lock may be applied to the new doors when the car is constructed.

35 Referring now more in detail to my invention and the enlarged views, Figs. 2, 3, 4 and 8 there is shown a plate 7 that is secured to the lower right hand corner of the door, this plate having a flange side member 8 which may be screwed or otherwise fastened to the edge of the door, the plate is also fastened at its upper left hand corner by a screw or rivet 9. This plate 7 is also 40 slightly offset throughout its length at 10 so that a strip of metal 11 may be placed beneath the offset portion 12 which strip 11 is bent about midway of its length to 45 form the pocket walls 13, and then extends parallel with the plate 7 and then is flanged 50 as at 14 to fit snugly around the edge of the door and to be fastened to the door on its inner side.

The offset portion 12 of the plate 7 is 55 also cut as at 15, the edges bent downwardly to lie along the side walls 13 of the pocket.

Before applying this plate 7 and its component strip 11, a pocket 17 is cut into the lower edge of the door so that the pocket walls $\frac{1}{2}$ may snugly fit therein. After this 60 plate has been fastened, rivets or bolts 18 will be passed through the strip 11 and through the plate 7 to securely fasten these two parts to the door.

Angularly secured by rivets to this plate 7 65 is a hasp and bolt member 19 which is a con-

ventional one, it being positioned however, angularly rather than vertical as in most instances.

Referring now to the other member of the lock, that is, that part which is fastened to 70 the frame of the car below the door, it will be seen that this likewise consists of a plate or strip 20 (see Fig. 5) which is flanged at one end as at 21 which flange is driven into the wood, or the wood is first cut out for the 75 reception of this end; this plate being secured by the numerous bolts 22 which pass entirely through the framework of the car. A strong upright or standard 23 is shown 80 which is preferably formed integral with the plate 20 and extends downwardly for some distance below the plate, and to which standard is pivotally secured the relatively thick arm 24, this arm being designed to snugly fit within the reinforced pocket 17. This arm lies flat against the upright when in its 85 uppermost position, the upright being nearly as long as the arm, thus a supporting wall for the arm to hold it against lateral movement in the rearward direction.

90 At the lower end of this arm, that is when the arm is in a position as shown in Fig. 3, there is placed an eye 25 which has been previously passed through the latch 26, this eye 25 being pressed or welded in the 95 arm 24. The latch 26 is provided with a small cut out portion 27 which is passed over the hasp on the member 19 when the arm 24 has been swung upwardly into the reinforced pocket 17. One of the guide brackets 100 5, heretofore mentioned, is riveted over the far end of the plate 20 which is clearly shown in the several figures.

After the latch member 26 has been passed over the hasp, the conventional locking bolt 28 on the hasp member 19 will be passed through the hasp and the conventional seal 29 passed through the slot 30 in the locking bolt 28.

The operation of the lock is extremely 110 simple and a short description only is necessary.

To lock the door, the door will be simply moved to its closed position as shown in Fig. 3, the arm 24 then registering with the pocket will be swung upwardly into the pocket 17, it abutting against the metal edges 115 16 and the rear wall of the pocket 13 formed in the plate 11, and the latch then placed over the hasp of the member 19 and the bolt 120 28 shot into place.

Of course, in unlocking the door, the operation is simply reversed when the door may be swung to its open position.

125 The many advantages of a lock of this kind will be readily apparent, the chief of which is that the arm 24 fitting snugly within the pocket prevents any longitudinal shifting of the door, and the strain, of course, falling on the relatively thick arm 24 130

and on the metal parts of the reinforced pocket; these parts being especially designed to withstand the strains and therefore not likely to be broken or torn from their position which is so often the case with the locks now in use.

Furthermore not only is the door held from longitudinally shifting but by swinging the arm into its pocket and then placing 10 the latch over the hasp the door is held against any lateral movement.

Of course the bracket guides are designed to hold the door against lateral movement, but it is well known that robbers or people 15 unauthorized to open the doors will sometimes lift the door so that the lower edge of the same will be above the guide bracket and entrance may be gained to the car without breaking the lead seal.

20 With my construction, it will be seen that this is impossible as the arm 24 when in its position and the latch member over the hasp, the door, although it may be slightly raised, cannot be raised so that it can be disengaged from the guide brackets and even 25 were this possible, it could not swing laterally enough to give admission to the car.

From the foregoing it will be seen that I have provided a lock wherein all of the 30 strain falls on an arm that is especially provided for this purpose and wherein none of the strain is placed on the latch or hasp, so that although I use a hasp and latch member I do not subject them to the strain 35 that usually falls upon them.

Furthermore I have provided a lock that is extremely strong and is to be placed preferably, down in the right hand lower corner which will prevent the door from being 40 moved laterally by unauthorized persons and prevent unauthorized entrance to the car: and furthermore, the lock will hold the door steadily in position and prevent it from shifting longitudinally or laterally while 45 the car is in motion.

Also I have provided a lock that may be quickly applied to the doors now in use with but little effort and little expense or may be readily applied to cars under construction.

50 Many slight changes may be made in the plates or arms and latch members without departing in any way from the spirit and scope of my invention.

55 Having thus described a preferred form of my invention, what I desire to claim by Letters Patent is:

1. A lock comprising two plates one of which is provided with a pocket and a hasp 60 member, and the other of which is provided with a pivotal arm adapted to be swung upwardly towards said first mentioned plate into said pocket, and a latch secured to said arm and to be swung over the said hasp member.

2. A lock comprising two plates, one of which is provided with a pocket, a hasp and bolt, the other of said plates being provided with a relatively thick arm, adapted to be swung upwardly and inwardly and snugly 70 fit within said pocket, a latch swingingly secured to said arm and fitting over said hasp member when said arm is in said pocket and the bolt holding said latch in a locked position.

75 3. A lock for freight car doors comprising two plates one of which is to be secured to the door and the other to be secured to the framework beneath the door, one of said plates provided with a hasp and a 80 pocket formed by cutting a portion of the plate and bending the edges downwardly, a metal strip reinforcing said pocket, the other of said plates being provided with a standard, a relatively thick arm pivotally 85 secured to said standard and adapted to be swung into and tightly engage the walls of said pocket, a latch secured to the upper end of said arm to engage said hasp when said arm is in said pocket and a bolt on the 90 said hasp member to pass over said latch member and through said hasp to thereby hold the latch in its locked position.

95 4. A lock for freight car doors comprising two plates one of which is secured to the car door and the other of which is secured to the framework below the door, the upper plate being provided with a hasp member comprising a hasp and a bolt, a portion of the plate being cut to form a pocket, a metal 100 strip secured beneath the lower edge of said upper plate and bent to form reinforcing walls for said pocket, the lower plate provided centrally thereof with an upright standard, a relatively thick arm pivoted 105 near the lower end of said standard and said arm adapted to be swung upwardly into said pocket, said standard being the same thickness of said arm and of substantially two-thirds of the length of 110 said arm to thereby prevent any rearward lateral movement of said arm, a latch swingingly mounted at the lower end of said relatively thick arm and passing over said hasp when said arm is in said pocket, said arm thereby preventing any shifting and lateral movement of said car door.

115 5. A lock for freight car doors comprising two parts, one of which is to be secured to the door and the other to be secured to the framework beneath the door, one of said parts being provided with a pocket and a hasp, the other of said parts being provided with a standard, an arm secured to said standard and adapted to be swung 120 into said pocket and to be braced against lateral movement by said standard, a latch secured to the upper end of said arm to engage said hasp, and means for holding the latch in engagement with said hasp.

6. A lock for freight car doors comprising an upper and lower member, the upper of which is to be secured to the door and the lower to be secured to the framework beneath the door, the upper member being provided with a pocket along its lower edge and a hasp secured to said upper part and in a plane above that of the pocket, the lower member being provided with a standard, an arm secured to said standard and adapted to be thrown into said pocket and contact with said standard throughout the length of the latter, a latch secured to said arm and fitting over said hasp when said arm is in said pocket, and means for locking the latch and hasp together.

7. A lock for freight car doors comprising two plates, one of which is provided with a flanged side for engaging the edge of the door said plate being provided with a pocket and said plate being also offset near its lower edge, a strip of metal passing beneath the same and being bent substantially U-shaped substantially centrally thereof to form reinforcing walls for said pocket, one edge of said strip being flanged to also engage the edge of the door, a standard formed on the lower of said plates and an arm pivotally secured thereto adapted to be swung into said pocket and means for locking said arm in said pocket to thereby prevent any lateral or shifting movement of said door.

8. A lock for freight car doors comprising two members, one of which is to be secured to the door and the other to be secured to the car body, the upper member being provided with a pocket along its lower edge and a hasp also secured to the said upper member, the lower member being provided with an upright standard extending substantially to the lower edge of the car door and said upper member, an arm pivotally secured to the lower end of

the standard and contacting with said standard when said arm is thrown into said pocket, the said standard bracing said arm against lateral movement of the door, a latch secured to said arm and fitting over said hasp when said arm is in said pocket and means for holding the latch and hasp together.

9. A lock for freight car doors comprising two members, one of which is secured to the door, the other of which is secured to the car body, the member secured to the car body being provided with a pocket along its lower edge, a hasp also secured to said member, the lower member being provided with an upright standard, an arm pivotally secured near the lower end of said standard and adapted to be swung upwardly and snugly fit within said pocket and the adjacent faces of said arm and said standard contacting when said arm is in said pocket to thereby brace and prevent lateral movement thereof, a latch secured to said arm and means for locking the latch to said hasp.

10. In combination with a freight car door, a lock comprising a plate secured to the lower portion of said door, a pocket formed in the lower edge of said door and means for reinforcing the pocket and forming a metal wall parallel with a vertical axis of the door, a plate secured to the frame of the car and located directly beneath the plate that is secured to the door, said plate provided with a standard, an arm pivotally secured to said standard and adapted to be swung into said pocket and contact with the side walls of said pocket and said vertical rear wall of said pocket, means for locking the arm in position, and said arm thereby holding said door against lateral or longitudinal movement.

In testimony whereof I affix my signature.

GEORGE H. FAHRENBRUCH.
